(57) **CLAIM**

The ornamental design for a charge base for vacuum cleaner, as shown.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken lines shown in the drawings are included for the purpose of illustrating unclaimed portions of the charger base for vacuum cleaner and form no part of the claimed design.
